ENGINE STARTING MECHANISM

Application filed August 27, 1931. Serial No. 559,721.

This invention relates to engine starting mechanism and more particularly to anti-pump and anti-drift devices for engine starters.

In engine starting mechanism of the type in which a motor driven pinion is automatically traversed into and out of mesh with an engine gear, it has been found in certain installations that there is a tendency for the pinion to move back and forth or "pump" as the engine goes over its compression points, and under certain conditions this motion may be sufficient to cause demeshing of the pinion.

It is an object of the present invention to provide a novel device for holding a starting pinion in its operative position until the engine starts.

Another object is to provide such a device which holds the pinion fully meshed with the engine gear during cranking, but is automatically withdrawn to allow the pinion to be demeshed when the engine starts.

A further object is to provide such a device which functions also as an anti-drift means to frictionally retain the pinion in its idle position except when the starting motor is energized.

Further objects and advantages will be apparent to those skilled in this art from the following description taken in connection with the accompanying drawings in which:—

Fig. 1 is a side elevation partly in section of a preferred embodiment of the invention, the parts being shown in full lines in their idle position, and in dotted lines in driving position;

Fig. 2 is a plan view of the same;

Fig. 3 is a side view partly in section of certain elements of the drive shown in the positions assumed when the anti-pumping means is released;

Fig. 4 is a section taken substantially on the line 4—4 of Fig. 3;

Fig. 5 is a similar sectional view taken substantially on the line 5—5 of Fig. 1, showing in full lines the parts in normal position and in dotted lines the positions assumed at the initiation of the releasing action of the anti-pumping device;

Fig. 6 is a view similar to Fig. 1 of a second embodiment of the invention;

Fig. 7 is a plan view of the same;

Fig. 8 is a side view partly in section of certain elements of the drive shown in Fig. 6, the parts being in the positions assumed when the anti-pumping means is released;

Fig. 9 is a section taken substantially on the line 9—9 of Fig. 8; and

Fig. 10 is a similar sectional view taken substantially on the line 10—10 of Fig. 6.

Referring first to Fig. 1 of the drawings, there is illustrated a starting motor 1 having an extended armature shaft 2 arranged to support and actuate the starter drive. Power means in the form of a threaded shaft 3 and a driven head 4 are loosely mounted on the motor shaft 2 and are provided with a lost motion connection therebetween formed by a cam lug 5 on the driven head 4 and a bell 6 formed on the end of the screw shaft 3, overlapping the end of the driven head 4 and having a slot 7 to receive said lug. The lost motion between the power members 3 and 4 is normally taken up, and the lug 5 held against a shoulder 8 at the driving end of the slot 7 as illustrated in Fig. 5 by yielding means such as a torsion spring 9 connected between said power members.

The driven head 4 is connected for rotation with the motor shaft 2 by a yielding driving connection in the form of a spring 11 fixed at one end to a driving head 10 on the motor shaft as by means of a stud 12 and connected at its other end to the driven head as by means of a stud 13.

A driving member in the form of a pinion 14 is threaded on the power member 3 in position to be moved thereby into and out of meshing engagement with a member such as a flywheel 15 of the engine to be started, the pinion being moved into mesh with the engine gear upon actuation of the starting motor and being moved out of engagement therewith by the overrunning action of the engine gear when the engine starts.

According to the present invention means are provided for positively holding the pinion 14 in fully meshed relation with the engine gear 15 during the cranking operation in

spite of the uneven resistances to cranking of the engine member as the engine passes over its compression points. As herein illustrated, this means takes the form of a ⁵ 17 ¹⁸ ¹⁹ ²⁰ ²¹ ²² ²³ ²⁴ ²⁵ ²⁶ ²⁷ ²⁸ ²⁹ ³⁰ ³¹ ³² ³³ ³⁴ ³⁵ ³⁶ ³⁷ ³⁸ ³⁹ ⁴⁰ ⁴¹ ⁴² ⁴³ ⁴⁴ ⁴⁵ ⁴⁶ ⁴⁷ ⁴⁸ ⁴⁹ ⁵⁰ ⁵¹ ⁵² ⁵³ ⁵⁴ ⁵⁵ ⁵⁶ ⁵⁷ ⁵⁸ ⁵⁹ ⁶⁰ ⁶¹ ⁶² ⁶³ ⁶⁴ The operation of this embodiment of the invention is similar to that previously described, the latch 29 serving normally as an anti-drift for the pinion 14 by engaging the periphery of the flange 19 thereon, and during cranking serving as an anti-pump by falling in behind the flange 19 as indicated in dotted lines in Fig. 6. When the engine starts, the cam 24 is moved against the action of spring 28 into the position shown in Fig. 9, raising the latch 29, whereupon the pinion 14 is thrown back by the overrunning action of engine member 15 to its idle position where it is retained by the frictional engagement of the latch with the flange 19.

Although certain forms of the invention have been shown and described in detail, it will be understood that various other embodiments are possible and changes may be made in the proportions and arrangements of the parts herein illustrated without departing from the spirit of the invention as defined in the claims appended hereto.

What is claimed is:

1. In starter gearing for internal combustion engines, power means, a driving member connected thereto for automatic movement into and out of engagement with a member of an engine to be started, means for retaining said driving member in idle position until the power means are actuated and for thereafter locking the driving member in operative engagement with the engine member, and means for rendering said locking means inoperative when the engine starts.

2. In starter gearing for internal combustion engines, power means, a driving member connected thereto for automatic movement into and out of engagement with a member of an engine to be started, a latch for locking the driving member in operative engagement with the engine member, and means for moving said latch out of locking position when the engine starts, said latch being thereafter operative to frictionally retain the driving member in idle position.

3. In starter gearing for internal combustion engines, power means, a driving member connected thereto for automatic movement into and out of engagement with a member of an engine to be started, a latch pivoted to said power means, yielding means urging said latch in a direction to frictionally engage the driving member and retain it in idle position, said latch being arranged to positively lock the driving member in operative engagement with the engine member, and a cam member operative on a reversal of the direction of drive through the power means to release the latch from locking position and allow the pinion to return to idle position.

4. In starter gearing for internal combustion engines, power means including two elements connected for limited relative lost mo-

tion, a driving member connected to one of said power elements for automatic movement into and out of engagement with a member of an engine to be started, means mounted on one of said power elements for locking the driving member in operative engagement with the engine member, and means mounted on the other power element for rendering said locking means inoperative when the engine starts.

5. In starter gearing for internal combustion engines, power means including two elements connected for limited relative lost motion, a driving member connected to one of said power elements for automatic movement into and out of engagement with a member of an engine to be started, a latch mounted on one of said power elements for locking the driving member in operative engagement with the engine member, and a cam mounted on the other power element for moving said latch out of operative position when the engine starts.

6. In starter gearing for internal combustion engines, power means including two power members connected for limited lost motion, a driving member connected to one of said power members for rotation thereof and therewith, and connected to be moved thereby into and out of engagement with a member of an engine to be started, yielding means normally taking up the lost motion between the power members to provide a rigid drive therethrough, means mounted on one of said power members for holding the driving member in engagement with the engine member, and means on the other power member adapted upon a reversal of torque through said power members to move said holding means to inoperative position.

7. In starter gearing for internal combustion engines, power means including two power members connected for limited lost motion, a driving member connected to one of said power members for rotation thereof and therewith, and connected to be moved thereby into and out of engagement with a member of an engine to be started, yielding means normally taking up the lost motion between the power members to provide a rigid drive therethrough, means mounted on one of said power members adapted to engage a portion of the driving member and resist movement thereof away from idle position, said means being also arranged to resist disengagement of the driving member from the engine member, and means on the other power member operative on a reversal of torque through the power means to move said resisting means out of engagement with the driving member.

8. An automatic starter drive including a motor driven power means comprising a driving head and a screw shaft having a lost motion driving connection therebetween, a

pinion threaded on said screw shaft and adapted to engage and drive a gear of the engine to be started, a detent on one of the elements of said power means adapted to resist longitudinal movement of the pinion, and means on the other of said elements operative by virtue of said lost motion connection to disengage the detent.

9. An automatic starter drive including a motor driven power means comprising a driven head and a screw shaft having a lost motion driving connection therebetween, a pinion threaded on one element of said power means and adapted to engage and drive a gear of the engine to be started, said pinion having an annular flange fixed thereto, a latch on one element of said power means adapted to engage said flange and resist longitudinal movement of the pinion, and means on the other element of said power means operative by virtue of said lost motion connection to disengage the latch from said flange.

10. An automatic starter drive including a motor driven power means comprising a driven head and a screw shaft having a lost motion driving connection therebetween, a pinion threaded on one element of said power means and adapted to engage and drive a gear of the engine to be started, said pinion having an annular flange fixed thereto, a latch on one element of said power means adapted to frictionally engage said flange to resist movement of the pinion away from idle position and to abut said flange to prevent disengagement of the pinion from the engine gear and a cam on the other element of said power means operative by virtue of said lost motion connection to disengage the latch from said flange.

11. An automatic starter drive including a motor driven power means comprising a driving head and a driven shaft having a lost motion driving connection therebetween, a pinion mounted on said shaft for rotation thereof and therewith, and for longitudinal movement into and out of engagement with a member of an engine to be started, a member on one of the elements of said power means normally resisting longitudinal movement of the pinion, and means on the other of said elements brought into operation after taking up of the lost motion on reversal of the direction of drive between said elements to render said resisting means inoperative.

In testimony whereof I have signed this specification.

DANIEL P. KEARNEY.
